BUTTON ATTACHING MACHINE

John Nielsen, Beloit, Wis., assignor to American Pearl Button Co., Washington, Iowa, a corporation of Iowa

Application June 10, 1940, Serial No. 339,755

9 Claims. (Cl. 218—4)

This invention relates to a machine particularly designed for inserting fasteners in the shanks of shank type buttons after articles of clothing or display cards have been associated with the buttons by placing buttonholes thereof over the shanks of the buttons.

One object of the invention is to provide a unitary machine of simple, durable and inexpensive construction into which loose buttons and fasteners may be deposited and the machine, upon operation, feeds the buttons and fasteners into magazines from which they are discharged, the buttons being located in a predetermined position so that an element to which they are to be attached may be placed over the shank of the button, whereupon the machine may be selectively operated to insert the fastener in position for fastening the button to the element.

More particularly, it is my object to provide a machine in which a button hopper has a disc therein to pick up buttons from the hopper and discharge them into a button magazine, an escapement mechanism effecting proper release at the desired time of a button from the button magazine to a position where it is picked up and rotated by a push bar to proper fastener receiving position and then pushed by the bar to an operating position where the fastener is to be inserted therein.

Another object is to provide means for clamping the button at its operating position so that an element such as an article of wearing apparel or a display card may have a buttonhole therein fitted over the shank of the button prior to the insertion of the fastener into the shank.

Another object is to provide a fastener hopper from which the fasteners are taken by a pick-up disc and discharged into a fastener magazine, escapement mechanism being provided in connection with the fastener magazine to permit the fasteners to escape at the proper time to a position on a slide that opens up to let the fastener rotate to a properly aligned position with the shank of the button which is at operating position, a ram and fastening ejector mechanism being thereafter operable to advance the fastener toward the button shank and finally thrust it through the shank for thus attaching the button to the garment or card.

Still another object is to provide hopper and pick-up disc mechanisms for the buttons and fasteners, together with button and fastener magazines which are so designed that buttons and fasteners are fed in excess of requirements to the magazines and the excess buttons and fas-

teners dropped back into their respective hoppers.

Still another object is to provide a means for vibrating the button magazine to insure travel of the buttons therein by gravity without any trouble from sticking of the buttons with relation to the button magazine.

A further object is to provide a camshaft for operating the various mechanisms of my button attaching machine, the operating devices being spring advanced as permitted by cams on the shaft and positively returned by the cams so that any jamming of buttons or fasteners at any point in the machine will not result in breakage of parts of the machine, as the operating parts that coact with such a jammed button or fastener will merely remain thereagainst under the pressure of the spring until the cam returns it to its retracted position.

20 Further objects of my invention are to provide a clutch for operating the machine at the will of the operator one revolution at a time, regardless of whether the clutch pedal is held down or released; a friction drive means for the button and fastener pick-up discs to prevent breakage of machine parts in the event of jamming; simple ejector devices for each button and fastener pick-up pocket of the button and fastener pick-up discs operated by passing over rollers at the ejecting positions, and other features of construction which will hereinafter appear as the description of my invention proceeds.

With the foregoing as well as other objects in view, my invention consists in the construction, arrangement and combination of the various parts of my device whereby the objects contemplated are attained, as hereinafter more fully set forth, pointed out in my claims and illustrated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings, in which:

Figure 1 is a perspective view of a button attaching machine embodying my invention and illustrating it from the front where the operator stands or sits when operating it;

Figure 2 is an enlarged plan view as on the line 2—2 of Figure 1 showing the camshaft and various operating devices of my machine, a casting therefor being in section;

Figure 3 is an enlarged vertical sectional view on the line 3—3 of Figure 1 showing particularly a button hopper and magazine;

Figure 3a is a sectional view on the line 3a—3a of Figure 2;

Figure 4 is a sectional view on the line 4—4 of Figure 3 showing the button hopper and the intake end of the button magazine;

Figure 5 is an enlarged vertical sectional view on the line 5—5 of Figure 1 showing particularly a fastener hopper and magazine;

Figure 6 is a sectional view on the line 6—6 of Figure 5 showing the fastener hopper and the upper end of the fastener magazine;

Figure 7 is a vertical sectional view on the line 7—7 of Figure 2 showing a one position of a ram mechanism of my machine;

Figure 8 is a similar sectional view showing another position thereof;

Figure 9 is a similar sectional view showing still another position thereof;

Figure 10 is a sectional view on the line 10—10 of Figure 7;

Figure 11 is a sectional view on the line 11—11 of Figure 8;

Figure 12 is a sectional vertical view on the line 12—12 of Figure 2, and

Figure 13 is a rear elevational view of the mechanism shown in the upper right hand corner of Figure 2 and looking in the direction of the arrow 13 adjacent Figure 12.

On the accompanying drawings, I have used the reference characters 14 to indicate generally a supporting frame and T a top. A casing C is mounted on the top T. Most of the mechanism of my machine is mounted on the top T within the casing C. On the front of the casing C, I provide a button hopper 15 and a fastener hopper 16. Buttons B and fasteners F are adapted to be deposited loosely in the hoppers 15 and 16, respectively.

Referring to Figures 3 and 4, a button pick-up disc 17 forms a bottom for the button hopper 15. The disc 17 is frictionally driven from a shaft 18 in the following described manner: A friction washer 19 is positioned against a flange 20 of the shaft 18 and the hub of the disc 17 is positioned against the friction washer. A second friction washer 21 is positioned against the outer face of the disc and held thereagainst by a washer 22 and a nut 23. The nut 23 is screwed onto a reduced threaded portion 24 of the shaft 18 and is retained in its desired adjusted position by a lock nut 25.

The shaft 18 rotates in a bearing 26 and is driven from a shaft 27 by a worm 28 and a worm gear 29. The drive shaft 27 is continuously driven from a motor M by pulleys 30 and 31 and a belt 32.

The button pick-up disc 17 has a plurality of pockets 33 adjacent its periphery, into which the buttons B drop as the disc 17 rotates. The buttons B are of the type having shanks 34 of eyelet type and the buttons are retained in the pockets 33 and carried upwardly only when they enter the pockets 33 in a desired position, i. e., with the faces of the buttons against the bottoms of the pockets and the shanks 34 projecting toward the front of the machine.

Each pocket 33 is provided with an ejector pin 35 normally held in non-ejecting position by a spring 36. The ejector pins 35 successively pass over a single roller 37 supported by a bracket 38. The bracket 38 has a slot 39 receiving a cap screw

40 whereby the position of the bracket and thereby the roller 37 may be adjusted for the desired amount of ejecting movement of the ejecting pins 35.

The roller 37 is so located, as shown by dotted lines in Figure 4, that ejection occurs adjacent an intake extension 41 of a button magazine BM. The buttons fall against a guide 42 which directs them in a path so that they enter a slot 43 of the button magazine BM. The button magazine is provided with another and narrower slot 44 to permit passage of the button shank 34.

The button magazine BM, as shown in Figure 3, is inclined downwardly toward the front of the machine so that the buttons slide down it by gravity. To guide the buttons during such sliding movement, the button magazine includes a pair of plates 45, which plates define the slot 44. To aid the sliding movement these plates 45 are pivoted at 46 to the frame of the button magazine and are oscillatable about said pivot. These plates are pivoted adjacent their lower ends to a transversely slidable bar 47 having a downwardly and rearwardly inclined extension 48. The extension 48 carries a pin 49 entering a bifurcated lever 50. The lever 50 is mounted on a rockshaft 51 journaled at its forward end in a bearing 52 and at its rearward end in a bearing 53.

The rockshaft 51 at its rear end has a downwardly extending lever 54 connected by a spring 55 to the bracket 53. The spring 55 tends to rotate the rockshaft 51 clockwise, as viewed from the front of the machine.

The lever 54 is connected by a link 56 to a lever 57. The lever 57, as shown in Figure 13, is pivoted at 58 to a bearing member 59. The lever 57 carries a roller 60 designed to be engaged by a cam lobe 61 on a gear 62. The gear 62 meshes with an idler pinion 63 which in turn is secured to an idler gear 64. The idler gear 64 is rotated by a drive pinion 65 on the drive shaft 27. The gear 62 is rotatable on a camshaft 66 journaled in the bearing 59 and in another bearing 66, as shown in Figure 2.

After the buttons B pass the bar 47, they engage a button escapement mechanism including slidable pins 67 and 68. The pins 67 and 68 are secured to arms 69 and 70 which in turn are secured to a slidable shaft 71. The shaft 71 is urged toward the left by a spring 72 to engage a set screw 73 of a bell crank 14. The bell crank 14 is rotated counterclockwise in Figure 2 by a link 75 having an end 76 to engage a pin 77 of the bell crank 14, as shown in Figure 3. The link 75 is part of a second link 78 pivoted at 79 to a slidable plate 80. The plate 80 is slid by a link 81 and a lever 82. The lever 82 is pivoted to a stationary shaft 83 and carries a roller 84 to engage a cam 85. A spring 86 serves through its connection with a bell crank 87 to urge the roller 84 toward the cam 85. The cam is mounted on the camshaft 66, while the bell crank 87 is connected with the link 78.

After the buttons leave the escapement pins 67 and 68, they slide down a more steeply inclined portion 88 of the slot 43 of the button magazine BM (see Figure 3). They come to rest on a plate 90 (see Figure 3a) held against ledges 91 of a pair of guide bars 92 by a light spring 93. The shank 34 in this position of the button B is usually not properly aligned for receiving a fastener.

The button arriving at the point just described (which is indicated as B' in Figures 2 and 3a)

is then shifted to an operating position B'' by a push bar 94. The push bar 94 is secured to a block 94a. The block is slidably arranged in ways 94b and is propelled by the bell crank 87 through a link 95 connecting the block 94a with the bell crank. The push bar 94 has a notch 96 and a pair of inclined faces 97 and 98 serving as an entrance to the slot for the purpose of engaging the button shank 34 and turning the button until the shank is aligned with the slot 96 just prior to entry into the slot. This arrangement causes the shank of the button at the position B'' to have its eye opening toward the rear of the machine so that a fastener F can be readily inserted therein by the machine.

The fastener hopper 16 has associated therewith a fastener pick-up disc 99, as shown in Figure 5. The disc 99 forms a bottom for the hopper 16. The disc 99 is of the same general character as the button pick-up disc 17 of Figure 3 and is driven in a similar manner. Accordingly, I will not describe it in detail but have applied the following reference numerals thereto: 18a, 19a, 20a, 21a, 22a, 23a, 24a, 25a, 26a, 28a, 33a, 35a, 36a, 37a, 38a, 39a and 40a. The parts just enumerated correspond to similar parts in connection with the button hopper omitting the "a". The pockets 33a are of a different shape from the pockets 33 as they are designed to receive the fasteners F flatwise instead of receiving buttons. It will be noted that the pockets 33a are convex at one end and concave at the other end so that the fasteners will enter them only pointing in the proper direction.

After the fasteners are ejected by the ejector pins 35a, they enter a guide depression 100 and an intake member 101 of a fastener magazine FM, as shown in Figure 6. The fasteners first pass through a slot 102, then through an open space 103 and then into a slot 104 of the fastener magazine FM. Whenever there are excess fasteners, they may fall out through the open space 103 and back into the fastener hopper 16. The disc 17a has a plurality of webs 105 to engage the loose fasteners in the hopper and agitate them so that they will readily enter the pockets 33a.

The fasteners F slide down the fastener magazine FM guided by the slot 104 therein and the lowermost one finds its way onto a slide 106 (see Figures 7 and 10). The remaining fasteners are held back by an escapement pin 107 carried by a rockshaft 108. As shown in Figure 7, when the pin 107 is in its full line position it slides all but the lowermost fastener F slightly back up the slot 104 to permit free action of the fastener on the slide 106 for subsequent operations.

The rockshaft 108 is rotated toward the full line position of Figure 7 by a spring 109 (see Figures 2 and 10). The rockshaft 108 carries a downwardly extending arm 110 held by the spring 109 against a projection 111 of a bell crank lever 112. The bell crank lever 112 is pivoted at 113 and is urged to rotate clockwise in Figure 2 by a spring 114. A pull rod 115 extends loosely through a perforated end 116 of the bell crank lever 112 and is pivoted at its rear end to a pin 117 extending from a bell crank lever 118. The bell crank lever 118 carries a roller 119 engaging a cam 120 on the camshaft 66.

The slide 106, as shown in Figure 2, is urged toward the full line position of Figure 10 by a spring 121. The slide carries a pin 122 adapted to be engaged by the bell crank lever 112 for

retracting the slide 106 to the dotted position of Figure 10 at the proper time.

Next to the cam 119 on the camshaft 66 is a cam 123 cooperating with a roller 124. The roller 124 is carried by a bell crank 125, the downwardly extending arm of which is relatively long, as shown in Figure 5. The lower end of this arm is connected by a link 126 to a bell crank 127 pivoted at 128. A spring 129 tends to rotate the bell crank lever 127 clockwise and the bell crank lever carries a set screw 130 adapted to contact at times with the button supporting plate 90.

Referring to Figures 7 and 10, a slidable ram 131 is illustrated having a groove 132, as shown in Figure 11, receiving a fastener ejector bar 133. The forward end of the bar 133 is indicated at 134 in Figure 7. The forward end of the ram 131 has a guard 135 secured thereto. When the slide 106 opens to the dotted position of Figure 10, the fastener F lying thereon is turned a quarter turn and drops through a slot 136 into the groove 132 of the ram 131, as shown by dotted lines in Figure 7. The ram 131 and its ejector bar 133 then move forwardly to the position shown in Figure 8 with the guard 135 over a card or other element 137 that has been positioned with a buttonhole 138 thereon over the shank 34 of the button B by the operator, as shown in Figure 7. Thereafter the ejector bar 133 pushes the fastener 30 to the final position of Figure 9 as the ram 131 is started in a retracting direction. Finally the ejector bar 133 also returns.

The sliding movements of the ram 131 and the ejector bar 133 are controlled by links 139 and 140, respectively. The rear ends of the links are pivoted to bell cranks 141 and 142, respectively, which as shown in Figure 2 carry rollers 143 and 144. Springs 143a and 144a connected with arms 141 and 142 cause the rollers 143 and 144 to normally coat with cams 145 and 146 on the camshaft 66. All of the bell cranks 118, 125, 141 and 142 are pivoted on the stationary shaft 83 and held against axial movement thereon by a collar 147 fixed to the shaft.

To operate the camshaft 66 at the proper time desired, I provide a clutch mechanism, shown in Figures 12 and 13, which will now be described. The continuously rotating gear 62 has a collar 148 provided with a plurality of sockets 149. Another collar 150 is secured to the camshaft 66 and has slidably therein a key 151. The key 151 is urged by a spring 152 toward the collar 148.

A vertically slidable member 153 has a cam surface 154 to coat with a shoulder 155 of the key 151 and a flat spot 153a at one end of the cam face. The cam surface 154 pulls the key 151 out of any socket 149 in which it may be lodged and the shoulder 155 of the key comes to rest on or before it reaches the flat spot 153a when the momentum of the cam shaft 66 and its associated parts has been spent. The member 153 is urged upwardly by a spring 156 so that it will serve to withdraw the key at a predetermined point in the revolution of the camshaft 66, and such withdrawal will occur each time the cam shaft 66 reaches said predetermined point.

Shoulder 155 of key 151 normally rests upon cam surface 154 or flat spot 153a and to start the camshaft 66 to rotating, I provide a member 157 pivoted at 158 to a vertically slidable rod 159. A spring 160 urges the rod upwardly. The member 157 has a shoulder 161 to engage a projection 162 of the member 153. Whenever the rod 159 is pulled downwardly, it also pulls the member

153 downwardly so that the key 151 is permitted to drop into one of the sockets 149. The key almost immediately thereafter, during its rotation, engages a curved face 163 of the member 157 to swing it toward the left in Figure 12 against the bias of a spring 164a, pressing against a pin 164b, thereby releasing the member 153, in case the rod 159 is held down so that its spring 156 can raise it again. This pivoting of element 157 by the key 151 permits spring 156 to act even though element 161 has been held depressed and thus insures that the cam surface 154 will be elevated, and therefore in a position to pull pin 151 from that one of the sockets 149 that it happens to be engaged in whether the rod 159 is pulled downwardly and then released, or whether it is held downwardly.

For the purpose of pulling the rod 159 downwardly, I provide a cable 164 passing over and under pulleys 165 and 166 and attached at its lower end to a treadle 167 conveniently positioned so that the operator can depress it by means of his foot.

Practical operation

In the operation of my button attaching machine, the hopper discs 17 and 99 rotate continuously as long as the motor M is energized by means of a conveniently located switch 168. The operator deposits a supply of buttons in the hopper 15 and a supply of fasteners in the hopper 16, whereupon the machine is ready for the operation of fastening buttons to display cards or garments.

When the treadle 167 is depressed, it will first operate the ram mechanism and thereafter bring a button to operation position B'' in Figure 2. The ram mechanism and the button positioning mechanism are operated as a result of depression of the pedal 167 moving the member 157 downwardly. In rest position shoulder 155 of key 151 is normally on the flat spot 153a of member 153. The member 157 has its shoulder 161 overhanging the shoulder 162 of the member 153, as shown in Figure 12, and therefore the member 153 is moved downwardly with the member 157. This will result in the flat spot 153a of the member 153 moving downwardly to a position where it no longer registers with the shoulder 155 of the key 151 and the key 151 will therefore drop into one of the sockets 149 of the gear 62.

Since the gear 62 is continuously rotating, the key 151 will then be carried with the gear and in turn will rotate the collar 150 and the camshaft 66. During the first part of such rotation, the key 151 engages the cam face 163 of the member 157 and swings this member toward the left, against the bias of the spring urged pin 164b. This operation releases the shoulder 161 from the member 153 so that the spring 156 will raise the member 153 to its initial position.

The camshaft 66, through its cam 145, the roller 143, the bell crank 141 and the link 139, moves the ram 131 from the position of Figure 8 to the position of Figure 7 against the bias of the spring 143a. The tension of spring 143a moves the ram 131 in reverse direction. The ejector bar 133 is similarly moved under the action of its spring 144a and in reverse direction by the cam 146, the bell crank 142 and the link 140. Movement of the ram and ejector will eject a fastener without a button being in position to receive the fastener. Such operation is necessary, however, to start the machine for proper operating cycles.

Following the initial operation of the ram and fastener as just described, the push bar 94 will engage a button at position B' due to the cam 85 operating the roller 84, the lever 82, the link 81, the slide 80, the link 78, the bell crank 87 and the link 95 against the bias of the spring 86. The inclined portions 97 and 98 of the slot 96 of the push bar 94 will engage the shank of the button and rotate it to a properly aligned position for subsequent reception of a fastener. The button will be pushed by the push bar to position B'' for receiving the next fastener to be ejected from the ram.

Thereupon the set screw 130 (see Figure 8) is permitted to be raised by the spring 129 (see Figure 5) as the lobe of the cam 123 leaves the roller 124 and thereby permits the bell crank 123 and the link 125 to be moved by the spring. The set screw will engage the clamp bar 90 for clamping the button at position B'' against a pair of spring plates 92a, as shown in Figure 3a, so that the shank 34 of the button is rigidly held with the button at position B'' for the fastener insertion operation to be performed in the next cycle of operation of the machine.

One revolution of the camshaft is then completed and the camshaft rotation stopped by the shoulder 155 of the key 151 engaging the cam surface 154 of the member 153. The cam surface, being inclined with respect to a plane of rotation normal to the axis of the shaft 66, will slide the key 151 to the left (in Figure 13), thus disengaging it from the socket 149 in which it has been located. As the shaft 66 rotates at a relatively slow speed and the rollers against the cams of the camshaft constitute some drag, the shaft will stop almost immediately with the shoulder 155 of the key not beyond the flat spot 153a of the member 153.

We now have a button held in position where the operator may place a buttonhole of the display card or garment over the shank of the button and again depress the treadle 167 to cause a fastener F to enter the eye of the shank 34 of the button at position B''. When the treadle is so depressed, the ram and ejector mechanism will operate as already described, the ram 131 moving to the position of Figure 8 and thereafter the ejector 133 ejecting the fastener from the ram to the position of Figure 9. The ram and the ejector then start on their return movements. The clamp plate 90 is then released by lowering of the set screw 130 caused by the lobe of the cam 123 lifting the roller 124 and rotating the bell crank 127 (Figure 5) counterclockwise against the action of the spring 129 and through the bell crank 125 and the link 126.

This completes a second cycle of operation and a second revolution of the camshaft 66, during which the escapement pins 67, 88 and 107 for the buttons and fasteners operate at the proper times. The escapement pins 67 and 68 are operated against the bias of the spring 12 through the plunger 71, set screw 73, bell crank 74, pin 77 and end 76 of the link 75 from the slide 80 operated by the cam 85. The escapement pin 107 is operated by the cam 120 through the roller 119, the bell crank 118 and the link 115 against the bias of the spring 114.

The various cams on the camshaft are properly set for the desired timing of the different mechanisms operated by the shaft. The escapement pin 67 (shown in Figure 2) is in the path of a shank of a button in the magazine BM. As the cam 85 starts to rotate, the set screw 13 will be retracted

so that the spring 72 will move the pin 67 out of the path of movement of the shank and the pin 68 into its path of movement to prevent the button from gravitating to a position against the rear side of the push bar 94. When the push bar is retracted, the plunger 71 will be forced toward the right by the set screw 73, thus releasing the button shank with respect to the escapement pin 68 so that the button will slide down to position B' for the next operating cycle. At the same time, the escapement pin 69 will move to position to stop the next button.

The escapement pin 107 is rocked forwardly at its lower end (dotted position in Figure 7) and the bar 106 is then moved to its dotted position (Figure 10) before the ram 131 starts moving forwardly. The pin 107 is rocked forwardly by the cam 120 through the roller 119, the bell crank 118, the rod 115 and the part 111 of the bell crank 112 engaging the arm 110 of the rock shaft 108 and rocking it against the bias of the spring 109. The bell crank 112 also engages the pin 122 of the bar 106 to move it against the bias of the spring 121.

From the standpoint of the operator, it is merely necessary to see that the hoppers are provided with buttons and fasteners and to place display cards or garments in position to receive the button shank, then depress the treadle for each fastener inserting operation desired, and after the fastener is inserted remove the card or garment with the button fastened thereto or shift the card or garment to position for another inserting operation.

It will be noted that all of the mechanisms are spring actuated in an advance direction so that if buttons, fasteners or foreign materials become jammed in any part of the machine the operating devices will stop against them under bias of the springs without breaking the machine. A hand wheel 169 is mounted on the drive shaft 127 for convenience in slowly rotating the machine by hand during adjustments or while clearing out obstructions from the operating parts.

Having described one specific embodiment of my invention together with the operation thereof, I desire it to be understood that this form is selected merely for the purpose of facilitating disclosure of the invention rather than for the purpose of limiting the number of forms which it may assume. It is to be further understood that various modifications, adaptations and alterations may be applied to the specific form disclosed to meet the requirements of practice without in any manner departing from the spirit and scope of the present invention except as set forth in the claims appended hereto.

I claim as my invention and desire to secure by Letters Patent of the United States:

1. A button attaching machine including means for positioning buttons periodically at an operating position, a fastener magazine, means for supplying fasteners to said magazine, fastener escapement mechanism for releasing said fasteners one at a time from said fastener magazine and pushing the remaining fasteners therein rearwardly to clear the released fastener, a slide mechanism to receive the released fastener at one end of the slide thereof, said slide being operable to permit the fastener to drop over the end thereof and turn substantially a quarter revolution and fall into a vertical position, ram mechanism for receiving the fasteners, a guard on said ram mechanism, a fastener ejector mechanism in said ram mechanism, means for moving said

ram mechanism, guard and fastener ejecting mechanism to a position adjacent the shank of a button positioned by said positioning mechanism, and means for moving said fastener ejecting mechanism of said ram relative to the ram mechanism to eject a fastener therefrom to a position where it grips said shank of said button.

2. A button attaching machine including means for positioning buttons periodically at an operating position, a fastener magazine, means for supplying U-shaped fasteners thereto, fastener escapement mechanism for releasing said fasteners one at a time from said fastener magazine, ram mechanism to receive the released fastener, a fastener ejector mechanism in said ram mechanism, means for moving said ram mechanism and said fastener ejecting mechanism of said ram to a position adjacent the shank of a button positioned in operating position by said button positioning mechanism, and reciprocating means for moving said fastener ejecting mechanism of said ram relative to the ram mechanism to a position wherein one leg of said fastener enters a perforation in said shank of said button.

3. A button attaching machine comprising means for positioning buttons periodically at an operating position, a fastener magazine, means for supplying fasteners thereto, fastener escapement mechanism for releasing said fasteners one at a time from said fastener magazine, ram mechanism to receive the fastener in a predetermined position, a guard on said ram mechanism, means for moving said ram mechanism and said guard to a position adjacent a button positioned by said positioning mechanism, and means for moving said fastener out of said ram to a position gripping said shank of said button while still covered by said guard and for retracting said guard and ram while retaining said fastener in its shank gripping position.

4. In a button attaching machine, button positioning mechanism, a fastener magazine having an intake end adapted to receive U-shaped fasteners and means comprising a reciprocating element having an initial position adjacent an exit end of the magazine for receiving fasteners one at a time and an advanced position removed therefrom when one leg of said fastener enters a perforation of a shank of said button.

5. In a button attaching machine, a button magazine, button escapement mechanism for releasing the buttons successively from the button magazine, positioning mechanism for engaging the released buttons and moving them to an operating position, said last mechanism having means to align the eye of the button and a shank thereon in part ever-receiving position, clamping mechanism having an operative position temporarily anchoring said button in said operating position wherein a buttonhole of an element to which the button is to be attached may be placed around said shank while in a position at rest without displacing said button from said operating position, and mechanism engaging a U-shaped fastener and moving it to a position wherein one leg of the fastener enters said eye and the fastener thereupon grips said shank of said temporarily anchored button.

6. In a button attaching machine, means for feeding buttons to an operating position, a fastener hopper, a fastener magazine, fastener escapement mechanism having periodic operation alternately releasing said fasteners one at a time from said fastener magazine and then pushing the remaining fasteners therein backward to

clear the released fastener, a slide mechanism to receive released fasteners in a horizontal position one at a time, means associated with said slide mechanism engaging the released fastener and adapted to turn the fastener laterally substantially one quarter revolution and into a vertical position, ram mechanism associated with the slide mechanism to receive the fastener in said vertical position, a fastener ejector mechanism in said ram mechanism, means for moving said ram mechanism and said fastener ejecting mechanism to a position adjacent the shank of a button in said operating position, and means for moving said fastener ejecting mechanism relative to the ram mechanism to a position wherein a fastener is ejected therefrom and grips the shank of said button.

7. In a button attaching machine, a button magazine, positioning mechanism for receiving buttons from said magazine and moving them to an operating position, clamping mechanism for buttons in said operating position wherein a buttonhole of an element to which the button is to be attached may be placed around the shank of the perforated button without displacing the button from said operating position, and mechanism for inserting one leg of a U-shaped fastener in the perforation of said shank of said button when held by said clamping mechanism.

8. In a button attaching machine, button supplying mechanism, positioning mechanism for engaging buttons supplied thereto and moving them to an operating position, said last mechanism having means to align a perforated shank of the button in a fastener receiving position, clamping means for temporarily fixing the button in said fastener receiving position and means for advancing a U-shaped fastener to button engaging position and thereafter inserting one leg of said fastener in the perforation of said shank while the button is in clamped position.
9. In a button attaching machine, button positioning mechanism including a clamping element adapted to hold a button in fastener receiving position, fastener supplying mechanism, a ram mechanism to receive fasteners from said fastener supplying mechanism, a fastener ejector mechanism in said ram mechanism, means for moving said ram mechanism and said fastener ejecting mechanism to a position adjacent the fastener receiving position of a button, and means for moving said fastener ejecting mechanism relative to the ram mechanism to a position wherein a fastener is ejected therefrom and grips a button, said ram thereupon starting in a retracting direction while said ejecting mechanism retains the fastener in gripping position.

JOHN NIELSEN.
